(57) **CLAIM**

The ornamental design for a pipe crimping tool with associated collar attachment, as shown and described.

DESCRIPTION

FIG. 1 is a first side perspective view of a pipe crimping tool with associated collar attachment showing my design; FIG. 2 is an opposing second side perspective view thereof; FIG. 3 is a first side perspective view thereof with the associated collar attachment in a detached configuration; FIG. 4 is a first side view thereof; FIG. 5 is an opposing second side view thereof; FIG. 6 is a back view thereof; FIG. 7 is front view thereof; FIG. 8 is a bottom view thereof; and, FIG. 9 is a top view thereof.

The broken lines in the drawings illustrate portions of a pipe crimping tool with associated collar attachment which form no part of the claimed design.
